UNITED STATES PATENT OFFICE.

ANDREW JAMES HARRISON, OF BIRMINGHAM, ENGLAND.

DESIGN FOR A SPECTACLE-FRAME.

47,420.

Specification for Design.

Patented June 8, 1915.

Application filed August 24, 1914. Serial No. 858,329. Term of patent 7 years.

To all whom it may concern:

Be it known that I, ANDREW JAMES HARRISON, subject of the King of Great Britain, residing at 11^A North Western Arcade, Birmingham, in the county of Warwick, England, have invented a new, original, and ornamental Design for Spectacle-Frames, of which the following is a specification, reference being had to the accompanying drawing, forming a part thereof.

In the drawing Figure 1 is a perspective view of a spectacle frame showing my new

design. Fig. 2 is a plan view of the frame shown in Fig. 1. Fig. 3 is a sectional side elevation of the frame shown in Figs. 1 and 2.

I claim:—

The ornamental design for a spectacle frame as shown.

ANDREW JAMES HARRISON.

Witnesses:

HAROLD J. C. FORRESTER,
MARY PARKES.
